SLAB TURNING DEVICE

William A. Ezell, Poland, Ohio

Application July 18, 1941, Serial No. 402,969

5 Claims. (Cl. 214—1)

This invention relates to a slab turning device and more particularly to a device adapted for use in a steel mill capable of turning billets or slabs primarily for effecting the removal of scale from the surfaces thereof.

A further object of the invention is the provision of a slab or billet turning device wherein portions thereof comprise table-like rolls capable of movement so that a slab or billet may be moved onto or off of the slab turning device.

A further object of the invention is the provision of a device making possible the utilization of the scale removing actions of conveyer table rolls.

It is well known that in reducing a billet one of the first stages comprises a reduction of the billet to a slab which slab is eventually reduced by successive stands of rolling mills to desirable thicknesses of material comprising plate, skelp and other primary steel products.

It is also well known that the slab ready for reduction upon leaving the heating furnace usually carries a considerable amount of scale upon the surfaces thereof which scale is a direct result of oxidation of the metal and which scale is objectionable and, therefore, it is desirable that the scale be removed as completely as possible prior to the principal reduction of the steel slab.

It has been determined that in passing the slab over the conventional conveyer tables which comprise a plurality of revolving rolls, the action of the rolls against the surface of the slab tends to break up and remove the scale. In order that the scale can thus be removed from both of the large surfaces of the slab it is, therefore, desirable that means be employed to turn the slab after it has traveled a reasonable distance so that the scale removing action takes place upon both the lower and uppermost surfaces of the slab as in progressing toward the stands of the rolling mill. The device comprising this invention provides for the turning of the slab and it is, therefore, placed in the conveyer table route preferably midway between the heating furnace and the first stands of the rolling mill.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a top plan view of the slab turning device showing the elevating arms thereof in flat horizontal position. Dotted lines illustrate the position of a slab on the device prior to the turning operation.

Figure 2 is an end elevation of the slab turning device showing the elevating arms thereof in elevated position. Dotted lines thereon illustrate the position of a slab about to be turned by the elevating arms.

By referring to the drawing and Figure 1 in particular it will be seen that a slab turning device comprising a rectangular frame having side sections 10 and end sections 11, the side sections 10 carrying between them in transverse position a plurality of rotatably positioned table rolls 12 the neck portions of which are carried in suitable bearings in the side section 10 of the frame and shaft-like extensions 13 are adapted to be connected by any suitable means to a power source (not shown).

By referring to Figure 2 of the drawing it will be noted that the uppermost surfaces of the table rolls 12 form a plane somewhat above the level of the rectangular frame of the device. It will thus be obvious that the slab turning device, when positioned with the end sections 11 of the frame adjacent other suitable conveyer tables, will be in a position to receive slabs thereon and capable of delivering slabs thereto.

By referring again to Figure 1 it will be seen that positioned between and below the end sections 11 of the frame and the rolls 12 there are channel-like structures or tracks 14 in each of which is positioned a pair of elevating arms. Each of the pairs of elevating arms comprise a bifurcated member 15 and an elevating member 15A attached thereto. Each of the bifurcated members 15 is provided at its free end with a roller 16 and with a pair of upturned projections 17 which are adapted to engage the edges of a slab positioned upon the turning device. In order that the elevating arms may be operated, as illustrated in Figure 2, so that a slab may be efficiently turned thereby, a motivating shaft 18A is positioned lengthwise of the device at one side thereof and the outermost ends of the elevating arms 15A are securely affixed thereto as indicated at points 18; thus a partial rotating motion imparted to the motivating shaft 18A by any desirable means such as for example, through the arm 19 affixed thereto, will result in the rotation of the shaft and the upward movement of

the elevating arms 15A and bifurcated members 15 and any slab that may be positioned on the slab turning device. Pivots 20 establish movable connection between the elevating arms 15A and the bifurcated members 15. In order that slabs rolling onto the turning device from adjacent conveyer tables will be guided into desirable position thereon, lengthwise guide members 21 are positioned at each side of the device adjacent the side members 10 of the frame and their outermost ends are suitably shaped to effectively guide a slab into position for the turning operation.

By referring now to Figure 2 of the drawing it will be observed that at such time as the elevating mechanism comprising the elevating arms 15A and the bifurcated members 15 have reached the position therein illustrated, a slab carried upon the bifurcated members 15 will be brought into engagement with a pair of movably positioned blocking members 22 the outermost ends of which are preferably formed with a radius so that they will not damage the surface of the slab and which blocking members 22 are preferably of inverted L-shape design and movably positioned on pivots 23 between structural supporting assemblies 24 which in turn are preferably affixed to and form a structural part of the rectangular frame and particularly the side section 10 thereof, against which they are positioned.

As illustrated in Figure 2 the bifurcated members 15 when moved sidewardly along the channels 14 on the rollers 16 will bring a slab positioned thereon, as illustrated in dotted lines, into engagement with the outermost ends of the blocking members 22 and thus cause the slab to be tilted outwardly therefrom and thus turned over and dropped back upon the table rolls 12 of the turning device from whence, upon the movement of the rolls 12, the slab may be delivered onto an adjacent conveyer table. It will thus be seen that as the slab approaches the turning device the action of the conventional table rolls will cause a loosening of the scale on the bottom of the slab and its removal therefrom and that by turning the slab as through the operation of the device herein described and illustrated the other side of the slab may be then subjected to the same scale removing action of successive conveyer tables as the slab travels on toward the rolling mill.

Again referring to Figure 2 of the drawing it will be noted that the channel 14 is formed with a slight elevation 14A at one end thereof which is adapted to cause the bifurcated members 15 to move upwardly at the approximate moment that the slab is tilted outwardly therefrom by reason of the action of the blocking members 22 thereagainst. This action facilitates the rapid tilting or tipping of the slab and insures its accurate positioning upon the table rolls 12 after it has fallen thereon thus completing the turning operation satisfactorily.

In summary it will be observed that a slab moves upon the turning device from an adjacent conveyer table. The table rolls 12 of the device are stopped and suitable motion imparted the elevating mechanism which in turn picks up the slab, moves it sideways and tips it over thus effectively turning it. With the elevating arms and bifurcated members still in elevated position and in extreme side position the table rolls 12 of the device are caused to move and the slab is moved off the turning device onto an adjacent conveyer table. The elevating mechanism com-

prising the elevating arms 15A and the bifurcated members 15 are then lowered into position and the device is ready for repeated operation.

It will be obvious that any suitable power source such as a hydraulic piston mechanism, a power driven eccentric or any other practical device may be employed to impart the partial motion necessary to the elevating mechanism. It will also be obvious that automatic limit controls of a conventional form and design may be employed so that a slab rolling onto the turning device will automatically activate the turning device and upon its being turned will in turn activate other controls of a conventional type to cause the slab to move off the turning device. It will thus be seen that the slab turning device permits the full utilization of the scale removing action of the conveyer rolls and results in a slab delivered to the mill in relatively clean condition. It will be further observed that the device when provided with automatic controls is completely automatic in operation and does not necessarily need the attention of an operator.

What I claim is:

- 25 1. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 30 2. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 35 3. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 40 4. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 45 5. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 50 6. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 55 7. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 60 8. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 65 9. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 70 10. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.
- 75 11. In a slab turning device including a roller table having transversely positioned tracks, elevating mechanism adapted to lift and turn a slab thereon, said mechanism comprising a plurality of hinged arms positioned transversely of the said table on said tracks, said arms arranged in pairs and pivoted together at adjacent ends, one of each pair of the said hinged arms pivoted to the said table at one side thereof, and means for imparting upward movement to the said hinged arms so as to lift and tip a slab thereon.

arms so as to lift and tip a slab thereon, said means comprising a rotatable shaft forming the said pivot between the said arms and the said table, rollers positioned on the free ends of each pair of the said hinged arms together with means formed on the free ends of each of the said arms adapted to engage the edge of a slab thereon.

5. The combination of a roller table having transversely positioned tracks and mechanism for lifting and tipping over a slab thereon, said mechanism comprising a plurality of hinged elevating members positioned transversely of the

6 said table on said tracks, said arms arranged in pairs and pivoted together at adjacent ends, and normally below the uppermost surfaces of the said roller table, means for elevating the said hinged elevating members, each of the said elevating members pivoted to the roller table side at one side thereof, and blocking members supported above the roller table in position to be engaged by a slab being elevated, whereby the slab is caused to assume an inverted position on the roller table.
